LADY'S TOTE BAG

Ralph A. Muscatiello, Norwood, Mass., assignor to The Gillette Company, Boston, Mass., a corporation of Delaware

Filed Mar. 11, 1965, Ser. No. 84,218

Term of patent 14 years

(Cl. D87—3)

FIG. 1 is a top plan view of a lady's tote bag showing my new design, in open condition;

FIG. 2 is a front elevational view thereof;

FIG. 3 is a bottom plan view thereof;

FIG. 4 is an enlarged top view of the bag in closed condition, portions of the drawstrings and the bottom of the bag body being omitted for convenience of illustration; and

FIG. 5 is an enlarged cross-sectional view of the bag in open condition, portions of the drawstrings and the bag body being omitted for convenience of illustration.

Portions of the drawstrings are omitted in FIGS. 4 and 5 for convenience of illustration.

I claim:

The ornamental design for a lady's tote bag, substantially as shown and described.
